2,510,223
TWIN GLIDER SWING
Fred W. Hart, La Grange, Ind.

Application June 9, 1945, Serial No. 598,430

1 Claim. (Cl. 155—63)

1
This invention relates to amusement and pleasure devices and has for its object to provide a glider swing for two children.

Another object of the invention is to provide a swing with pivoted tilting seats through means of which the swing is largely operated.

A still further object of the invention is to provide a swing having foot treadles for assisting in operating the same.

Another object of the invention is to provide a swing of the above stated nature in which handles are provided for by means of which a child will be able to hold on to the seat when throwing its weight back to tilt the seat and assist in propelling the swing.

Other features and advantages will become more readily apparent from the following description and the accompanying illustrative drawings in which:

Figure 1 is a top plan view of my improved glider swing.

Figure 2 is a side elevational view thereof.

Figure 3 is an end elevational view of the device.

Figure 4 is a sectional view on line 4—4 of Figure 2, and

Figure 5 is a sectional view taken on line 5—5 of Figure 2.

Like reference characters denote like parts in both the drawings and specification in which 10 indicates my invention which consists of a framework 11, including uprights 12, 13, 14 and 15, connected by braces 16, 17, 18 and 19. The members 12 and 13, are connected at the upper ends by a head-piece 21, and directly below a spindle 22, which extends through a bore (not shown) in a rocker member 23, to which a depending bar 24, is attached.

The members 14 and 15, are likewise provided with a head connecting piece 25, and a spindle 26, to which a depending bar 21, is pivotally connected.

To the lower extremity and to the opposite sides 28 and 29, of said bars are pivotally connected by pins 30 and 31, a pair of horizontal bars 32 and 33. To the outer edges 34 and 35, of bars 24 and 27, are attached outwardly extending seats 36 and 37, the inner bifurcated extension portions 38 and 39, of which straddle the bars 24 and 27, respectively with the terminals 40 and 41. The seats are supported by brackets 42 and 43, the arms 44 and 45, of which extend horizontally under the seats to about the rear edges 46 and 47, of the seats and the vertical arms 48 and 49, 55

of the brackets project down along the sides 34 and 35, respectively of the bars 24 and 27, and are securely attached thereto.

Handle bars 50 and 51, are attached to bars 24 and 27, on the inner sides 52 and 53, thereof. Foot treadles 52' and 53', are fixed to bars 32 and 33, by their depending wings 54 and 55, and bolts 56, and at a proper distance from the seats 36 and 37. Foot braces 57 and 58, connect the respective lower ends of the uprights at 59, 60, 61 and 62.

As the seats 36 and 37, extend entirely beyond the terminals 63 and 64, of the horizontal supporting member 65, formed by members 32 and 33, and as pins 30 and 31, form a fulcrum therefor, the weight of a child on one seat pushing with her feet against the treadle adjacent the same will tend to throw the other seat away and up and the weight of the other seat coming down and a similar action of a child thereon will cause the first seat to swing back and rise; the action can be continued indefinitely with very little effort on the part of the users of the swing, the projecting weight on each end accomplishing most of the necessary power to operate the swing.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

40 A swing comprising a support including a pair of oppositely disposed inclined trapezoidal frames, crossed side braces connected between the upper ends of the frames, head members connected between the upper ends of the sides of each of the frames, bearing spindles mounted between the sides of each of the frames below the head members, rocker members swivelly secured to the spindles, parallel depending bars securely affixed to the inner surfaces of the rocker members for oscillatory movement on the spindle, base rails pivotally connected at their opposite ends to the lower ends of the bars, foot plates secured to said base rails and extending laterally therefrom, outwardly extending seats having inner bifurcated extension portions rigidly connected to the

outer edges of said bars, support brackets connected with the lower surface of the extending seats and the bars, and handle bars directly secured to the inner surface of the bars above the seats.

FRED W. HART.
